UNITED STATES PATENT OFFICE.

ANCER B. LEFFEL, OF SPRINGFIELD, OHIO.

DISPLAY-RACK.

1,378,692.

Specification of Letters Patent. Patented May 17, 1921.

Application filed December 6, 1920. Serial No. 428,711.

To all whom it may concern:

Be it known that I, ANCEL B. LEFFEL, a citizen of the United States, residing at Springfield, in the county of Clark and State 5 of Ohio, have invented new and useful Improvements in Display-Racks, of which the following is a specification.

My present invention has reference to a displaying apparatus for fabrics.

10 The primary object of the invention is the production of an apparatus of this character especially designed for displaying lace curtains or such like fabrics, wherein the fabric holding member is hollow, having
15 compartments in which the ends of curtains to be displayed are arranged, suitable weighted means retaining the curtains in their pockets, a sheet, comprising a back-ground for the curtain being connected with
20 the holding means and depending through an opening in the bottom of the hollow member between the pockets, while the said holding means is hingedly arranged on a suitable support, whereby the same may be swung to
25 conveniently and properly display the curtains.

A further object is the construction of a display apparatus for lace curtains or the like which is of a simple construction, which
30 may be cheaply manufactured, easily installed, and thoroughly efficient for the purpose for which it is devised.

I accomplish the foregoing objects, and others which will appear as the nature of the invention is better understood, by a construction, combination and operative arrangement of parts, such as is disclosed by the drawings which accompany and which form part of this application.

40 In the drawings:—

Figure 1 is a perspective view showing the curtains supported for display in accordance with this invention.

Fig. 2 is a transverse sectional view 45 through one of the supporting members.

Fig. 3 is a sectional view approximately on the line 3-3 of Fig. 2.

Fig. 4 is a horizontal sectional view

line 4—4 of Fig. 2.
50 The other figures illustrate details.
My improvement is designed for displaying lace curtains or the like in stores, and includes a frame that is preferably constructed of angle irons, the same constituting side
55 members and an upper member or members connecting the sides. Each of the sides in-

cludes a base 1 from which arises an upright 2. Between the rear portion of the base angle iron and the upright angle iron 2 there is a brace 3, while secured to the outer faces of the uprights 2 at and adjacent to the top thereof are longitudinal angle members 4 and 5 respectively. The angle flanges of the members 4 and 5 are extended in an outward direction with respect to the frame, and are, at determined intervals provided with registering openings. Through these openings pass pivots 6 that also pass through openings in the upper and lower arms 7 and 8 respectively of bracket members 9. The lower arm 8 of each of the brackets is connected to the upper arm by a vertical member 10, the said upper arm 7 being connected to the inner and open end of the lace curtain holders 11. The holders or display members 11 are substantially square in cross section and are of a length greater than the width of the curtains which are suspended and displayed therefrom. The bracket 9 also includes an upwardly rounded member formed at the juncture of the vertical member 10 and the lower arm 8. This rounded portion of the bracket is indicated by the numeral 12, and enters the hollow holder 11 and is secured to the top thereof.

The outer end of each of the holder members 11, as previously stated, is closed, and each of the said members 11 is centrally provided with a longitudinal opening extending from the said closed end to the open end thereof. The opening is, of course, formed centrally in the lower wall 13 of the holder, and the said lower wall has its confronting edges formed with upstanding flanges 14. The flanges 14 terminate a suitable distance away from the top 15 of the holder, and provide, in connection with the bottom 13 and the sides of the holder, two spaced compartments or pockets 16 respectively. Depending centrally from the top 15, through the opening 17, between the flanges 14, is a fabric sheet 18. The holder has its top provided with spaced openings for the reception of securing means 19 that attach the fabric sheet to the holder. The sheet 18 is designed to serve as a background for the curtains 20—20 to be displayed. Two of such curtains are arranged on each holder, the upper ends of the said curtains being received in the respective pockets 16. Before inserting the curtains in the pockets the upper edges thereof are

folded, as disclosed by the drawings, and in each of the folds I arrange a weighted cross sectionally rounded rod 21. These rods effectively sustain the curtains in their pockets, permit of the ready removal of the said curtains from the pockets, and also, if desired, may serve as roller members whereby the curtains may be adjusted.

As disclosed in Fig. 1 of the drawings, 10 a great number of holders are attached to the supporting frame, so that a plurality of curtains can be thus exhibited. It is, of course, to be understood that the improvement is not to be restricted for use as a 15 displaying apparatus for lace curtains, as other fabric materials can be likewise successfully suspended and displayed therefrom. Any of the holders may be swung 20 angularly of the supporting frame, by the operator grasping either the curtains or the fabric background sheet 18 to cause the holders to turn on the brackets which pivotally connect the same with the supporting frame, and it is thought that the foregoing 25 description, when taken in connection with the drawings will fully set forth the construction, advantages and operation of the device without further detailed description. It is thought necessary to state, however, 30 that I am not to be restricted to the precise details set forth in this description and disclosed by the drawings, but am entitled to all such changes therefrom as fall within the 35 scope of what is claimed.

Having described the invention, I claim:—
1. In a device for the purpose set forth, a support, curtain holders having one of their ends pivoted to the support, each of said holders comprising a hollow member having 40 a central opening in the bottom thereof and divided into pockets or compartments to the opposite sides of the openings, each of said compartments designed to receive therein the folded end of a drapery to be displayed, 45 and a weighted element in each of the folds of the draperies holding the ends of said draperies in said compartments.

2. In a displaying apparatus for fabrics, a support comprising a frame constructed of angle irons, hollow holders for the fabrics 50 to be displayed, pivotally secured to the longitudinal members of the support, each of said holders having its outer end closed and its bottom formed with a central opening extending entirely therethrough, the 55 bottom wall of the holder having upstanding flanges at the confronting edges thereof dividing the interior of the holder into spaced compartments or pockets, the fabrics to be displayed having their ends folded and 60 received in the respective compartments, and a cross sectionally round weighted element arranged in each of the folds for holding the upper ends of the fabrics in the 65 respective compartments.

3. In a displaying apparatus for curtains or like fabrics, a frame constructed of angle irons having the flanges of their upper longitudinal member outstanding and provided with spaced alining openings, brackets 70 including upper and lower arms arranged on said flanges, pivots passing through the arms and through the openings in the flanges, a hollow fabric display holder secured to and supported from each of the 75 brackets, each of said holders having its inner end opened and its outer end closed, its bottom, from its said closed end provided with a central opening which extends entirely therethrough, the confronting edges 80 of the bottom having upstanding flanges providing the holder with spaced compartments or pockets, a fabric sheet comprising a background secured to the top and depending centrally between the flanges, the curtains to be displayed arranged to the opposite sides of the sheet and having their upper 85 ends folded and received in the respective pockets or compartments, and a cross sectionally round weighted element received in 90 each of the folds for holding the said ends of the fabrics in the respective compartments.

In testimony whereof I affix my signature.
ANCEL B. LEFFEL.
